(57) **CLAIM**

The ornamental design for a cutting-tool holder used for grinding, as shown and described.

DESCRIPTION

FIG. 1 is a perspective view of a cutting-tool holder used for grinding showing my new design;

FIG. 2 is a front view thereof;

FIG. 3 is a top view thereof

FIG. 4 is a bottom view thereof;

FIG. 5 is a left side view thereof, the right side being a mirror image thereof; and,

FIG. 6 is a perspective view of the embodiment in condition of use.

The broken line showing of the knife and a stone in FIG. 6 is for illustrative purposes only and forms no part of the claimed design.
